UNITED STATES PATENT OFFICE.

BENJAMIN L. ALTIC, OF ROANOKE, VIRGINIA.

GLASS-CUTTER.

1,109,274.

Specification of Letters Patent.

Patented Sept. 1, 1914.

Application filed February 18, 1914. Serial No. 819,424.

To all whom it may concern:

Be it known that I, BENJAMIN L. ALTIC, a citizen of the United States, residing at Roanoke, in the county of Roanoke and State of Virginia, have invented certain new and useful Improvements in Glass-Cutters, of which the following is a specification.

The object of this invention is to provide a convenient means for cutting circular or other plane figures from sheets of glass or other material, its most general application being to the art of cutting glass disks.

15 In the drawings, Figure 1 is a plan view of the cutter of my invention and Fig. 2 a side elevational view, partly in section, of the same.

In glass cutters as now used for this purpose a similar device is used except that the pivot or post is held in place on the glass by pressure of the hand, the base of the pivot usually being supplied with a rubber suction cap.

25 A description of my invention follows in which reference is made to the accompanying drawings, like numbers representing the same parts wherever they occur.

1 represents a glass cutter's table and 2 30 a sheet of glass lying thereon. To the underside of the table 2 I affix the winding of an electro-magnet 3, the core 4 of the same extending upward through the table, the face of the core being adjacent to the underside of the plate of glass. The winding of this electro-magnet is connected to any suitable electric circuit, a switch being provided in the circuit.

The glass cutter 5 is mounted in any suitable holder 6 and the holder is clamped to a radius bar or cutter bar 7 by means of a movable clamp 8.

45 The cutter bar 7 is preferably graduated so that the disks may be readily cut to any desired diameter. The cutter bar 7 is pivoted at its inner end 9 on a vertical pintle 10 which pintle is rigidly secured to and forms a part of the center post 11. The upper end of the pintle 10 is threaded to 50 accommodate a nut 12.

The space between the shoulder 13 of the post 11 and the bottom of the nut 12 is slightly greater than the height of the hub 14 of the cutter bar 7. This allows the

cutter to be raised off the glass without 55 lifting the post 11.

The post 11 is made of a metal such as iron or steel that will be attracted by a magnet and in the under side of the base I provide inserts 15 of rubber or similar 60 friction material which prevent the post 11 from slipping on the surface of the glass.

The operation of my invention is as follows: The core 4 being magnetized the magnetic lines of force will flow through 65 the glass 2 and when the cutter is placed over the core 4 the post or armature 11 will be drawn firmly down against the glass. The cutter bar may then be freely revolved and without the necessity of holding down 70 the center post by hand.

As previously stated, my invention might also be used for cutting other flat shapes such as ellipses and the like and may be used for cutting glass or similar materials. 75

Having thus described my invention what I claim as new and desire to secure by Letters Patent is:

1. In a glass cutting arrangement the combination of a table adapted to support 80 a plate of glass, a magnet having the coil and core thereof mounted in said table, the face of said core being adjacent to the under side of the plate of glass, a post disposed on the upper side of the plate of glass and 85 being held against the same by the magnetic attraction, a portion of said post forming a vertical pintle, a cutter bar rotatably mounted on said pintle, and a glass cutter secured to said cutter bar, substantially as 90 described.

2. In a glass cutting arrangement the combination of a table adapted to support 95 a plate of glass, a magnet having the coil and core thereof mounted in said table, the face of said core being adjacent to the under side of the plate of glass, a post disposed on the upper side of the plate of glass and being held against the same by the magnetic attraction, a cutter bar rotatably mounted 100 on said post, a glass cutter secured to said cutter bar, and friction inserts in the base of said post, substantially as described.

3. In a glass cutting arrangement the combination of a table adapted to support 105 a plate of glass, a magnet having the coil and core thereof mounted in said table, the face of said core being adjacent to the under

side of the plate of glass, a post disposed on the upper side of the plate of glass, and being held against the same by the magnetic attraction, a cutter bar rotatably secured to said post, and a glass cutter movably secured to said cutter bar, substantially as described.

In testimony whereof I affix my signature in presence of two witnesses.

BENJAMIN L. ALTIC.
